UNITED STATES PATENT OFFICE

162,833

HOUSEHOLD MIXER

Alfonso Iannelli, Park Ridge, Ill., assignor to John Oster Manufacturing Company, Racine, Wis., a corporation of Wisconsin

Application November 22, 1950, Serial No. 13,099

Term of patent 14 years

(Cl. D44—8)

To all whom it may concern:

Be it known that I, Alfonso Iannelli, a citizen of the United States residing at Park Ridge, in the county of Cook and State of Illinois, have invented a new, original, and ornamental Design for Household Mixer, of which the following is a specification, reference being had to the accompanying drawings, forming part thereof.

Figure 1 is a perspective view of a household mixer, showing my new design and viewing the same from the front and one side;

mixer from the back and the opposite side and showing the bottom thereof.

I claim:

The ornamental design for a household mixer, as shown.

ALFONSO IANNELLI.
